UNITED STATES PATENT OFFICE

CHRIST DE YOUNG, OF CHICAGO, ILLINOIS, ASSIGNOR TO INTERNATIONAL HARVESTER COMPANY, A CORPORATION OF NEW JERSEY

STAMPING MACHINE

Application filed August 11, 1928. Serial No. 298,968.

This invention relates to an improvement in stamping machines or punch presses.

The particular improvement is in a feeding mechanism for regulating the feed of the work to be operated upon, the same including safety mechanism for preventing injury by the stamping or punching element to the operator's hand.

The objects of the invention are to provide in such machines having a feed table, a means for holding a piece of work to be stamped or punched in its work holding position, and a second means controllable by the feed of a succeeding piece of work to release the holding means, the purpose of such mechanism being to make it unnecessary for the operator, when feeding work, to get his hand into a position where it might be injured by the stamping or punching member. Another object is to provide an obstructor element which will prevent a careless operator from getting his hand injured. Other objects should be apparent as the disclosure progresses.

Briefly, these desirable objects are accomplished by the structure of this invention, which generally comprises in the combination with a stamping or punching machine having a stamping or punching element and a feed table, of means defining a passage-way along said table for the work, and interrelated holding and releasing means adjacent said passage-way for controlling the feed of work through the passage-way to punching position in such a manner that the operator need not injure his hands. An obstructor element is also provided, which doubly insures the operator's hand against injury.

Referring now to the drawings showing an illustrative embodiment of this invention, it will be seen that,—

Figure 1 is a general side elevational view of a standard stamping machine or punch press;

Figure 2 is a detail plan view, partly in section, of the feed table, the feed passage-way, the hold and releasing means, and the obstructor of this invention;

Figure 3 is a detail front elevational view in reduced scale of the structure shown in Figure 2; and

Figure 4 is a general side elevational view of the holding and releasing means of this invention adjacent the feed passage-way, as viewed substantially along the line 4—4 of Figure 2.

For the sake of illustration a conventional stamping machine has been shown which, as seen in Figure 1, comprises legs 10, a body 11, an inclined feed table 1, a punch or stamping element 13, and means 14 generally indicated for reciprocating the punch element 13 to and from stamping position as is well known in this art.

The table 12, as best shown in Figures 2 and 3, carries a pair of guide members 14 and 15 arranged in parallelism and spaced apart to form a work feeding passage-way 16 open at each end, as shown, so that a piece of work shown at 17 may be slid by hand therethrough to a position on the table, where it will slide into the path of movement of the punch element 13 to be punched or stamped. In the form of this invention herein shown, the thought is to stamp a trade-mark or other designation on the piece of work, as indicated in Figure 2.

The guide 15 is in the form of an upper plate 15^a and a lower plate 15^b spaced apart by a pin 18 at one end and another pin 19 at the other end. This spaced apart arrangement of the plates 15^a and 15^b forming the guide element 15 leaves a chamber in which is pivotally mounted on the pin 19 a lever 20 having a leg 21 and a holding projection 22, said lever being normally pressed out by a spring 23 to a position causing the projection 22 to extend into the passage-way for the purpose of holding the piece of work 17 in stamping position on the table, as shown in the full line position in Figure 2. At the entry end of the passage-way, the guide 15 carries, pivotally mounted on the pin 18, a similar lever 24, which includes a projection 25 and a leg 26, said projection 25 normally extending into the passage-way 16 because the spring pressed leg 21 of the lever 20 normally urges the leg 26 of the lever 24 in that direction, as will be clear, and as shown in the full line position in Figure 2. A stop pin 27 is provided for the lever 20 to limit its outward

movement and a similar stop pin 28 is provided for the lever 24 to limit the outward movement of this lever.

Bolts 29 serve to secure the guides 14 and 15 securely to the table. One of the guides, as for example the guide 14, carries on a post 30 an obstructor in the form of an arm 31, which can be adjustably swung into several positions by means of a nut 32 to cause said arm 31 to assume any desired position across the passage-way 16 with respect to the work 17 to be stamped, so that an operator cannot get his hand into the path of movement of the punch or stamping element 13, as will be understood.

In operation, the operator slides a piece of work 17 past the projection or obstruction 25 on the lever 24, as the same will yield back to permit this passage of the work, said piece 20 of work sliding down the table by gravity to the full line position shown in Figure 2, where the projection 22 of the lever 20 serves to hold the work in a position to be operated upon by the stamping element 13, it being understood 25 that the spring 23 normally holds the lever 20 and its projection 22 in a position to hold the work, as has just been described. After the work has been stamped, a succeeding piece 30 of work shown in the dotted line position in Figure 2 at 17' is slid by hand down the passage-way, which work 17' will contact the projection 25 of the lever 24, causing the arm 26 of this lever to be pivoted inwardly and, as the arm 26 will obviously move the arm 21 35 also inwardly, the extension or projection 22 of the lever 20 will also fold inwardly to cause the piece of work 17, which has already been stamped, to be released and discharged. As soon as the piece 17' passes the extension 40 25 on the lever 24, the spring 23 causes the levers to move outwardly again, so that the extension 22 will again be in work holding position. In this manner succeeding pieces 45 of work are fed through the passage-way, the pivoted levers serving to make it unnecessary for the operator to get his hand into the path of movement of the punch head.

In the event that the operator would be 50 careless in spite of this safety feed feature just described, it might be desirable that an obstructor in the form of an arm 31 also be provided, as has been described, so that a positive means will be provided for making it impossible for an operator to get his hand above 55 the work 17 and in the path of the punch head.

From this description it must now be appreciated that an improvement has been provided for machines of the character described, 60 which will make hand feeding in these machines safe for the operator, and that the invention accomplishes all of the desirable objects in this respect heretofore recited.

It is the intention to cover all such changes 65 and modifications of the form of the inven-

tion herein described and illustrated as do not materially depart from the spirit and scope thereof as indicated in the following claims.

What is claimed as new is:

1. The combination with a stamping machine having a punch member and a work holding and feeding table including a work passage-way, of means at one side of the passage-way for holding a piece of work in position to be stamped by the punch member, and means at the same side of the passage-way for releasing said holding means controlled by a second piece of work fed along the table. 70

2. The combination with a stamping machine having a punch member and a work holding and feeding table, of pivoted means adjacent the path of movement of work on the table for holding a piece of work in position to be stamped by the punch member, and other pivoted means on the same side of said path of movement and controlled by a second piece of work fed along the table to release said holding means. 80

3. The combination with a stamping machine having a punch member and a work holding and feeding table including a work passage-way, of yieldably mounted means at one side of said passage-way for holding a piece of work in position to be stamped by the punch member, and other yieldable means at the same side of the passage-way for releasing said first means controlled by a second piece of work fed along the table. 90

4. The combination with a stamping machine having a punch member and a work holding and feeding table, of a pivoted lever at one side of the table including means for holding a piece of work in position to be stamped by the punch member, and a second pivoted lever at the same side of the table for releasing the first lever. 100

5. The combination with a stamping machine having a punch member and a work holding and feeding table, of a spring pressed pivoted lever including means for holding a piece of work in position to be stamped by the punch member, and means controlled by the feeding of a succeeding piece of work to move said lever to release the first piece of work. 110

6. The combination with a stamping machine having a punch member and a work holding and feeding table, of a spring pressed pivoted lever including means for holding a piece of work in position to be stamped by the punch member, and a second pivoted lever controlled by a succeeding piece of work to move the first lever to release the first piece of work. 120

7. The combination with a stamping machine having a punch member and a work holding and feeding table, of a lever at one side of the table including means for holding a piece of work in position to be stamped, a 125

second lever at the same side of the table engaging the first lever and controlled by the feed of a second piece of work to move the first lever to release the first piece of work, and resilient means acting normally to keep 5 the first lever in work holding position and the second lever in a position to act as a yieldable obstruction to the feed of a second piece of work.

8. The combination with a stamping machine having a punch member and a table, of guide members on the table spaced to form a work feed passage-way, means in one of said guide members for holding a piece of work in position to be stamped, and other means in one of said guide members controlled by the feed of a succeeding piece of work for moving said first means to release the first piece of work.

9. The combination with a stamping machine having a punch member and a table, of guide members on the table spaced to form a work feed passage-way, pivoted means in one of said guide members for holding a piece 25 of work in position to be stamped, resilient means normally holding said means in said holding position, and another pivoted means in one of said guide members operable by the feed of a succeeding piece of work for moving 30 said first pivoted means against the force of the resilient means to release the first piece of work.

10. The combination with a stamping machine having a punch member and a table 35 including a work feed passage-way, of a work holding means adjacent said passage-way and releasing means adjacent said passage-way for releasing the holding means, said releasing means being controlled by the entry 40 of a succeeding piece of work into the feed passage-way.

11. The combination with a stamping machine having a punch member and a table including a work feed passage-way, of a yieldable work holding means adjacent said passage-way, and yieldable releasing means adjacent said passage-way for releasing the holding means, said releasing means being controlled by the entry 50 of a succeeding piece of work into the feed passage-way.

12. The combination with a stamping machine having a punch member and a table including a work feed passage-way, of a pair of yieldably and pivotally mounted levers 55 adjacent said passage-way, said levers engaging each other, one of said levers having means for holding work in stamping position and the other lever having means engageable by a succeeding piece of work entering the 60 feed passage-way to control the first lever to cause it to release the first piece of work after it has been stamped.

13. The combination with a stamping machine having a punch member and a work holding and feeding table, of means for hold-

ing a piece of work in position to be stamped by the punch member, means for releasing said holding means controlled by a second piece of work fed along the table, and an obstracter element to prevent entry of an operator's hand to a position in the path of movement of the punch member.

14. The combination with a stamping machine having a punch member and a work holding and feeding table, of means for holding a piece of work in position to be stamped by the punch member, means for releasing said holding means controlled by a second piece of work fed along the table, and an adjustably mounted obstracter arm to prevent entry of an operator's hand to a position in the path of movement of the punch member.

In testimony whereof I affix my signature.
CHRIST DE YOUNG.
